to Ivers-Lee Company, Newark, N. J., a corpo-
ration of Delaware

Application June 20, 1934, Serial No. 52,246

Term of patent 14 years

To all whom it may concern:

Be it known that I, Leroy L. Salfisberg, a citizen of the United States, residing at South Orange, in the county of Essex and State of New Jersey, have invented a new, original, and ornamental Design for a Package, of which the following is a specification, reference being had to the accompanying drawing, forming part thereof.

In the drawing Fig. 1 is a plan view; Fig. 2 is a side elevation; Fig. 3 is an enlarged fragmentary portion taken along the line 3—3 of Fig. 1;

and Fig. 4 is a side view of the representation of Fig. 3 showing my new design for a package. The distinctive feature of the design lies in the ornamental appearance of a centrally disposed transparent commodity-containing enclosure surrounded by an area of crossed corrugations providing a translucent border effect.

I claim:

The ornamental design for a package as shown and described.
